Attorney

UNITED STATES PATENT OFFICE

WILLIAM C. F. DIETZ, OF CINCINNATI, OHIO

FEEDING TABLE FOR CLOTHES WRINGERS

Application filed October 10, 1928. Serial No. 311,638.

This invention relates to an improved safety feeding mechanism for delivering moist or saturated fabrics to the compression rolls of a wringer, particularly wringers of the type employed in conjunction with power operated washing machines, although the invention in its broader aspect is applicable to the feeder or deliverer of all kinds of materials to a pair of compression elements 5 through which the materials fed are adapted to pass and this definition of course embraces hand operated wringers as well as the motor driven or power type.

Power operated wringers are usually provided with release devices, carried in connection with the frames thereof, whereby during the operation of the wringers should the fingers of the operator become caught between the compression rolls, said device will 20 function to permit of the relative separation of the rolls to release the hand. While these devices operate quite successfully it is the object of the present invention to dispense with their use through the employment of a 25 novel type of feed table so arranged in relation to the compression rolls that the moisture wet fabrics are placed by the operator on the feeding table with the fingers of the operator completely removed or spaced from 30 the compression rolls, the construction and operating position of the table then serving to automatically pass the fabrics into positions capable of being received by and drawn through the compression rolls.

It is another object of the invention to provide the frame of a clothes wringer with a pivoted feeding table adapted when in an operating position to occupy such an angle with respect to the vertical plane of the rolls 40 that the fabrics placed on the table may be fed, partly by gravity and partly by the pressure of the operator into engagement with the rolls.

It is another object of the invention to 45 pivotally mount the table on the frame so that it may be readily swung from operative to inoperative positions.

It is another important object of the invention to provide a feeding mechanism for 50 wringers of the character set forth wherein

the frame of the wringer is provided with a pair of feed tables pivotally secured thereto, said tables being interlinked so that when one of said tables assumes an operative feeding position in relation to the rolls, the other table will be positioned automatically to cover or protect the rear or discharge side of said rolls, preventing accidental injury to the operator from said latter side. 55

The invention further provides in the pivoted interconnecting mechanism between the tables, a pivoted drain plate, which cooperates with said rolls and the usual drain board to return the water released from the fabrics during their passage through the rolls to the 60 tub or other receptacle from which the fabrics may have been removed. 65

A still further object of the invention rests in directly connecting the pivoted drain plate by links with the pivoted feeding tables, so 70 that said drain plate will automatically assume a correct position of operation in accordance with the movement of the feeding tables.

Other objects reside in the provision of 75 mechanism of the character set forth which is of a simple, positive and efficient construction and which may be employed either as an attachment for standard types of clothes wringers or which in other instances may 80 constitute a unitary part of such wringers.

For a further understanding of the invention reference is to be had to the following description and the accompanying drawings, wherein:

Figure 1 is a view in front elevation of a 85 wringer provided with the feeding mechanism comprising the present invention,

Figure 2 is a top plan view of the wringer and the feeding mechanism,

Figure 3 is a vertical sectional view taken 90 on the line 3-3 of Figure 1.

Referring more particularly to the drawing the numeral 1 designates a standard or conventional type of clothes wringer. The 95 wringer comprises a frame which in this instance is of metallic construction although a wooden frame may be used if desired. The frame, which is designated by the letter A, consists of a base rail 2, vertical side rails 100

3—3 and a top rail 4. As shown, these rails are of hollow metallic design. The side rails are provided with journals (not shown) adapted for the reception of opposite longitudinal ends of a pair of vertically aligned roll shafts 5, and surrounding said shafts and located between the rails 3 and the compressible rolls 6, formed from rubber or other similar material. The shafts 5 may be connected by gears so that they rotate in opposite directions, as is customary in wringer constructions.

Secured to each of the rails 3 along the inner walls of the latter is a vertically extending sheet metal bracket 7, centrally and vertically slotted as at 8 to permit of the passage of the shafts 5 therethrough. Each of the brackets is formed with a pair of outstanding ears 9 to which are pivotally secured as at 10 a pair of feeding tables 11.

In this instance the tables 11 are of cast aluminum construction, although any other suitable material may be utilized. Each table is provided at the longitudinal ends thereof with laterally directed flanges 12 and the innermost of these flanges is pivotally secured as at 10 to the bracket 7, permitting the tables to swing about horizontal axes.

As shown in Figure 3 each of the tables 11 when in an operative position is situated in acute angular relationship to a vertical plane passing through the center of the roll 6. As a result of this position fabrics or other materials deposited upon the upper surface of the table 11 are fed by gravity, or may be partly forced by hand into a position where such fabrics may be positively engaged by the rolls 6 and drawn therethrough. This keeps the fingers or hands of the operator away or spaced from the rolls so that there is practically no possibility whatever of injury to the operator while engaged in operating the wringer. Each of the tables may have its upper or outer longitudinal edge provided with a roller 13 to facilitate the travel of fabrics along the table and for the purpose of minimizing friction.

The tables are linked together so that movement of one will pivotally actuate the other. This is accomplished preferably by pivotally connecting as at 14 a link 15 with the flanges 12 of each of the tables. The lower ends of these links are pivotally connected as at 16 with upturned flanges provided upon the longitudinal ends of a drain plate 17. This plate is pivotally mounted in the center thereof and as at 18 to the side flanges 19 of a major drain plate 20. The plate 20 is stationarily secured in the usual manner to the base rail 2 of the wringer frame and is provided with the oppositely sloping portions capable of collecting and receiving the water released from the compression rolls and to permit such water to drain back to

the tub or other receptacle from which the fabrics have been withdrawn.

It will be seen that by the inclusion of the pivoted minor plate 17 and the links 15 the tables will rock in unison about their horizontal pivotal connections with the wringer frame. Thus when one table is in an operative or feeding position the other table will assume an inoperative position so as to be out of the way of the fabrics which are advanced through the compression rolls. In addition to being moved automatically to an out of the way position the inoperative table serves to protect the rear or discharge side of said rolls, preventing the attendant or other persons from being injured by contact with the last named side of the wringer. The adjustment of the feeding tables also automatically adjusts the minor drain plate 17, swinging the latter about its pivotal axis 18 so that it may lie in a plane best adapted to control the return of water, released from the rolls to a desired point of discharge. It is preferable to curve or mount the lower longitudinal edge of each of the tables 11 where they engage with the lowermost roll 6, for the purpose of minimizing friction and preventing injury to the soft compressible material from which the roll is formed. The top rail 4 of the frame structure is provided with the usual compression spring 21 which operates to maintain the upper compression roll. The degree of compression imparted by the spring 21 may, of course, be governed by the usual adjusting means 22. It will be understood that the roll 6 may be revolved either by mechanical power delivered thereto, or manually, as desired.

What is claimed is:

1. In a clothes wringer provided with upper and lower wringer-rolls, feeding tables located on opposite sides of the rolls and arranged to swing toward and away therefrom, the pivoted connections of said tables being located at a point above the lower of said rolls so that upon the presentation of the tables to the rolls the same will be directed downwardly and angularly toward the lower of said rolls, and a connection between the tables whereby as one of the tables is presented to the rolls the other is swung away therefrom.

2. In a clothes wringer, a frame, upper and lower wringer rolls journaled in said frame, a pair of substantially parallelly arranged feeding tables located on opposite sides of said rolls, said tables being pivoted to the frame at points above the lower of said rolls and arranged to swing toward and away therefrom, and a connection between the tables for positioning the tables in a downward angular direction toward the lower of said rolls when in an operative position and to place the tables away from said lower roll when in an inoperative position.

3. In a clothes wringer, a frame, upper and lower wringer rolls journaled for rotation in said frame, a feeding table located on each side of said rolls and pivoted to the frame at a point above the lower of said rolls, the pivotal connection of the tables being located at the end of the latter at a point intermediate the longitudinal side edges thereof, a movable drain board pivotally connected to said frame structure, and a connection between the tables and the drain board, whereby as one of the tables is swung upon its pivots for presentation to one of the rolls the other is swung away therefrom, the tables when in an operative position being sloped downwardly and angularly towards the lower of said rolls.

4. In a clothes wringer, a frame, upper and lower wringer-rolls journaled to said frame, pivoted feeding tables secured to said frame structure and arranged on opposite sides of said rolls, the pivotal connections of said tables being located at the ends of the latter and positioned substantially half-way between the longitudinal side edges of said tables, and a connection between said tables for alternately presenting the tables to the rolls for feeding purposes, whereby due to the respective locations of the pivotal connections of said tables the same will take a downward inclined position towards the lower of said rolls.

5. In a clothes wringer, a frame, upper and lower wringer-rolls journaled in said frame, a pair of feeding tables pivotally mounted in connection with said wringers and arranged on opposite sides of said rolls, said tables having their pivotal connections located at the end and intermediate the longitudinal side edges thereof so that the tables will slope downwardly towards the lower of said rolls when in active use with the outer longitudinal edge thereof outside the pivotal point for the table, and the opposite edge positioned inside the pivot of said table.

In testimony whereof I affix my signature.
WILLIAM C. F. DIETZ.
